CLAIM

The ornamental design for an electrical power unit, as shown and described.

DESCRIPTION

FIG. 1 is a front perspective view of an electrical power unit showing our new design;

FIG. 2 is a rear perspective view thereof;

FIG. 3 is a rear elevation thereof;

FIG. 4 is a front elevation thereof;

FIG. 5 is top plan view thereof;

FIG. 6 is a bottom plan view thereof;

FIG. 7 is a left side elevation thereof; and,

FIG. 8 is a right side elevation thereof.

The broken lines in the drawings are for the purpose of illustrating portions of the electrical power unit that form no part of the claimed design.

1 Claim, 4 Drawing Sheets
